UNITED STATES PATENT OFFICE.

CLARENCE B. BATES, OF MARSHALLTOWN, IOWA.

DOOR OPENING AND CLOSING DEVICE.

Application filed April 4, 1927. Serial No. 180,815.

The object of my invention is to provide a door opening and closing device of simple, durable, and comparatively inexpensive construction.

- 5 More particularly my invention relates to a device of this character which can be applied to a garage for automatically opening the door thereof upon the approach of an automobile.
- 10 A further object is to automatically close the door after the automobile has passed through the door opening.

Another object of my invention is to provide floating platforms which are raised by 15 means of a spring tensioning device but which can be depressed by placing a weight thereon such as the front or rear wheels of an automobile.

Still another object is to connect the platforms to the garage doors themselves so that depression of the platforms will cause the doors to swing on their pivots.

Still a further object is to cause the depression of the platform to store up energy 25 for the closing of the doors as the platforms are released.

Still another object is to arrange a system of levers and links whereby the slight movement of the platforms will be magnified for the purpose of moving the garage doors through a considerable distance so that they can be brought to properly opened position.

Still another object is to provide a flexible connection in the device which allows 35 for variations in the distance the platforms are moved and yet allows the doors to be brought to fully opened or closed position.

Still a further object is to arrange the various parts of my device so that they are 40 assembled in a unitary structure which can be secured to the frame work of the door opening of any garage without any material alterations in the construction of the garage itself.

Still a further object is to provide a locking mechanism on the inside of the garage which when actuated will prevent the platforms from being depressed and in consequence maintain the doors of the garage 45 locked in closed position.

With these and other objects in view, my invention consists in the construction, arrangement and combination of the various elements of my door opening and closing

device, whereby the objects contemplated are 55 attained, as hereinafter set forth, pointed out in my claims and illustrated in the accompanying drawings, in which:

Figure 1 is an elevation of a portion of a garage and a garage door with my improved opening and closing device attached thereto as viewed from the inside of the garage.

Figure 2 is a sectional view taken on the line 2—2 of Figure 1 and illustrates the 60 doors of the garage in closed position and also in open position in dotted lines.

Figure 3 is an enlarged view partly in section of the unit secured to the right hand side jamb of the garage door and is illustrated from the inside of the garage showing the door in closed position.

Figure 4 is a sectional view taken on the line 4—4 of Figure 3.

Figure 5 is a sectional view taken on the line 5—5 of Figure 1 and illustrates the 70 pivotal connection of the outer ends of the platforms.

Figure 6 is a detail sectional view taken on the line 6—6 of Figure 5.

Figure 7 is an elevation similar to the one shown in Figure 3 but showing the parts in a different position as when the door is opened.

Figure 8 is a plan view of the unit illustrated in Figure 3 and showing in dotted lines the parts in the position illustrated in Figure 7.

Figure 9 is a detail sectional view taken on the line 9—9 of Figure 7; and

Figure 10 is a side elevation of the platforms illustrating the garage door in section.

Upon the accompanying drawings I have 95 used the reference numeral 10 to indicate generally the front wall of a garage.

The wall 10 is secured to a head jamb 12 and side jambs 14 which define a door opening 16. The door opening 16 is designed to be closed by the folding door elements 18 and 20. The door elements 18 are secured to vertical shafts 20 by bolts 22 or equivalent means. The door elements 20 are hinged to the door elements 18 by hinges 22.

The shafts 20 are journaled at their lower ends on studs 24 extending from brackets 26 which are secured to the side jambs 14 by lag screws 28 or by bolts if found desirable.

The upper ends of the shafts 20 extend through the openings 30 in the head jamb 12 and are journaled in brackets 32. The brackets 32 are provided for the purpose of supporting various parts of the operating mechanism of my device which parts will be hereinafter more fully described.

The door elements 20 have secured to their upper adjacent corners, brackets 34 which 10 rotatably support rollers 36. The rollers 36 are designed to travel in a channel member 38 which is secured in any convenient manner to the head jamb 12. From the foregoing description it will be obvious that rotation of the shafts 20 in one direction will cause the door elements 18 and 20 to fold together (the rollers 36 traveling away from each other in the channel member 38) whereby they are opened. Rotation of the 15 shafts 20 in the opposite direction will cause the doors to close. It may here be mentioned that any type of swinging door or folding door may be secured to the shafts 20 and that I do not wish to be limited to the 20 type of door illustrated.

For operating the door elements 18 and 20 for closing and opening them I provide a pair of platforms 40 and 42 which are actuated by the weight of an automobile as the 25 wheels thereof are driven on to one of the platforms. The platform 40 it will be noted is shorter than the platform 42 and is positioned on the inside of the garage. The platform 42 is made longer because there is 30 more room for it on the outside of the garage and it should be longer in order for the doors not to interfere with the automobile when it is driven onto the outside platform. The platforms 40 comprise inner frame 35 members 44 and outer frame members 46. The frame members 44 and 46 are connected by side frame members 48. The frame members 44, 46, and 48 are covered with planking 50 for the automobile to be driven over. 40 The frame members 46 have secured thereto peculiar Z-shaped bars 52. The Z-bars 52 are designed to hook over angle bars 54 which may be secured to the cement floor 56 or anchored in any suitable manner. In 45 the manner just described the outer ends of the platforms 40 and 42 are pivotally mounted. The platforms are also removable by merely lifting up on the Z-bar 52.

To prevent movement of the platforms 55 toward the door opening 16 when an automobile is driven thereonto, I provide a series of rivets 58 designed to drop into notches 60 formed in the angles 54. The heads of the rivets 58 engage the outer surfaces of 60 the angles 54 and thus prevent undesirable movement of the platforms.

For supporting the inner ends of the platforms 40 and 42 and at the same time for 65 operatively connecting them to the door operating mechanisms which are mounted on

the brackets 32 I provide links 62 which are pivoted on studs 64 secured to the inner frame members 44 of the platforms 40 and 42. There are four studs 64, one for each end of each member 44. The links 62 may 70 be held on the stud 64 by split spring rings 66 or equivalent means.

The two links 62 at each side of the door opening 16 are pivoted to a bracket 68. An actuating rod 70 extends slidably through 75 each bracket 68 and has a nut 72 on its lower end. A spring 74 is interposed between each nut 72 and the lower flange 76 of each bracket 68. The purpose of the springs 74 will hereinafter be described.

For maintaining the inner ends of the platforms 40 and 42 in raised position I provide the following described mechanism. Extending from each bracket 32 is a perforated ear 78. A piston rod 80 extends through each bracket 78 and is provided with a piston 82 on its lower end. An adjusting nut 84 and a lock nut 86 are screwed onto the upper end of each piston rod 80. The piston 82 is slidably mounted in a cylinder 88 having a head 90 provided with a ring 92. The ring 92 is adapted to be received in a hook 94 which is secured by set screw means to the rod 70.

The cylinder 88 is provided at its upper 95 end with a head 96 having a stuffing box 98 formed thereon. A heavy coil spring 100 is interposed between the upper head 96 of the cylinder 88 and the piston 82.

In the construction of the parts just described, it will be obvious that the spring 100 constrains the piston 82 and consequently the links 62 upwardly whereby a spring tension is exerted on the platforms 40 and 42 to maintain them in raised position.

For operatively connecting each rod 70 to a door operating shaft 20 I provide the following described mechanism. Pivoted on a shoulder cap screw 102 is an arm 104. Pivoted on a shouldered cap screw 106 is a toggle 110. A second toggle lever 110 is pivoted at 112 to the link 104 and the free ends of both toggle levers 108 and 110 have a pivotal connection in the form of a shouldered cap screw 114. The screw 114 also extends through an opening in the upper end of the rod 70 whereby the rod is connected to the toggle levers. It will be obvious from the foregoing description that a downward movement of the rod 70 will operate the toggle levers 108 and 110 to move from the position illustrated in Figure 3 to the position illustrated in Figure 7 of the drawings. This will swing the arm 104 in a counter-clockwise direction as also illustrated in these figures.

For operatively connecting the free end of the arm 104 to the outer end of an arm 116 which is secured to the upper end of the shaft 20 I provide a bracket 118. A link 130

120 has one end pivoted to the free end of the arm 104 by means of a shouldered cap screw 122. The other end of the link 120 is pivoted to the bracket 118 by a similar screw 124.

It will be noted by referring to Figure 9 of the drawings that the bracket 118 is angle shaped in cross section. Pivots secured to the horizontal portion of the bracket 118 is a link 126. The link 126 is pivotally secured by means of a shouldered cap screw 128 to the free end of the arm 116.

The bracket 118 is secured to a slide bar 129 in the following described manner. The cap screw 130 which pivotally secures the link 126 to the bracket 118 is provided with a reduced portion 132 adapted to extend through the bracket 118 and to be screw threaded into the slide bar 129. The shoulder 134 formed by the reduced portion 132 engages the upper surface of the bracket 118 and thereby securely clamps it to the slide bar 129. The portion of the cap screw 130 above the shoulder 134 is sufficiently long to allow free pivotal movement of the link 126 between the head of the cap screw and the bracket 118.

For slidably supporting the bar 129 I provide a pair of slide bearings 136 which may be formed on the bracket 32 or be made in a separate piece and secured thereto.

In the use of my device I have found it desirable to provide a lock for the doors. This can be accomplished by providing a mechanism to prevent the downward movement of the platforms 40 and 42 when an automobile is driven onto them. In Figure 4 of the drawings I have illustrated a locking arm 138 pivoted at 140 to the bracket 26. A link 142 is pivoted to the arm 138 and extends toward the inside of the garage as illustrated in Figure 10 of the drawings. It may here be mentioned that an arm 138 is provided for each side of the platforms.

A rod 144 is pivoted in the frame of the platform 40 and extends across it from side to side. One end of the shaft 144 is provided with a lever 146. Both ends of the shaft 144 are provided with short levers 148 to the lower ends of which the rods 142 are pivoted. When the levers 138 are moved from the position illustrated in Figure 4 to position under the studs 64 on the frame member 44 of the platform 42, downward movement of the inner ends of the platforms will be prevented.

Practical operation.

In the practical operation of my door opening and closing device it is merely necessary to run the front or back wheels of the automobile up on to either of the platforms 40 or 42 which will cause them to be depressed against the action of the springs 100 due to the weight of the automobile.

The device can be designed to operate for any desired weight. The weight of the automobile on the inner ends of the platforms 40 and 42 draws the rods 70 downwardly and thereby causes the hooks 94 to move the cylinders 88 simultaneously therewith. This action compresses the springs 100 and operates the toggle levers 108 and 110 to move the arms 104 to the position illustrated in Figure 7.

The swinging of the arms 104 causes the brackets 118 to move the bars 129 in their bearings 136. The links 126 swing the arms 116 thereby causing the shafts 19 to rotate and the doors 18 and 20 to be folded up to the dotted line position illustrated in Figure 2. To prevent a violent action of the device, the pistons 82 in the cylinders 88 act as dash pots inasmuch as the air trapped in the cylinders leaks past the pistons and makes their travel very slow.

In order to insure a full opening of the doors, the platforms 40 and 42 are designed to move farther than the rods 70. To allow for this difference of movement the springs 74 are compressed slightly when the platforms are completely depressed.

The toggle levers 108 and 110 are provided so that the slight movement of the platforms and of the rods 70 will be magnified by them. It will also be noted that the lever 104 increases the movement of the link 120 somewhat. This magnification of the movement is necessary in order to give a full swinging movement to the shaft 19 for fully opening the doors.

After the automobile has been driven through the door opening 16 and off the platforms, the compressed springs 100 are free to move the cylinders 88 upwardly and thereby raise the platforms and actuate the toggle levers 108 and 110, the arms 104, the links 120, and 126, and the arms 116 for closing the doors. The pistons 82 in closing again act as dash pots to prevent a too violent action of the springs 100.

When it is desired to lock the doors in closed position, it is merely necessary to move the lever 146 from the position illustrated in Figure 10 to the dotted line position illustrated in the same figure. In either position the weight of the lever 146 having passed over the pivot shaft 144 operates to maintain the locking levers 138 in the desired position.

Having described my invention it will be obvious that I have provided a door opening and closing device which operates entirely automatically upon an automobile being driven on to the platforms which extend from the door opening 16. When driven upon these platforms, the doors will be opened so that the automobile can pass through the door. Upon leaving the platforms the doors will be automatically closed.

due to the force stored up by the springs 100 which are compressed by the weight of the automobile.

Some changes may be made in the details 5 of the construction and arrangement of the various parts of my device without variation from the real purpose and object of my invention, and it is my intention to cover by my claims, any such modifications as may 10 be embodied within their scope.

I claim as my invention:

1. In combination with a wall having a door frame therein, a shaft rotatably mounted in said frame, a door secured to said 15 shaft, an arm on said shaft, a bar slidably mounted adjacent said arm, a second arm pivotally mounted adjacent said bar, link connections between said arms and said bar, a platform having one end pivoted, an operative 20 connection between said second arm and the free end of said platform and spring means for maintaining said free end in raised position.

2. In combination with a wall having a 25 door frame therein, a shaft rotatably mounted in said frame, a door secured to said shaft, an arm on said shaft, a bar slidably mounted, a second arm pivotally mounted, link connections between said arms 30 and said bar, a platform having one end pivoted, a pair of toggle links having one end pivotally mounted and the other end pivoted to said second arm, an operative 35 connection between said toggle levers and the free end of said platform and spring means for maintaining said free end in raised position.

3. In combination with a wall having a door frame therein, a shaft rotatably 40 mounted in said frame, a door secured to said shaft, an arm on said shaft, a bar slidably mounted, a second arm pivotally mounted, link connections between said arms and said bar, a platform having one 45 end pivoted and an operative connection between said second arm and the free end of said platform.

4. In combination with a wall having a door opening therein and a pivotally 50 mounted door adapted to close said door opening, means for operating said door comprising a bracket secured to the door frame of said wall, the pivotal mounting of the door extending through said bracket, an 55 arm on said mounting, a sliding bar on said bracket, a link connection between said arm and said bar, a second arm pivoted on said bracket at substantially right angles to the arm on said mounting, a platform mounted 60 for depression when a weight is placed thereon, a pair of toggle levers pivoted to

gether, and having their free ends pivoted to the bracket and second arm respectively and a link connection between said platform and the pivotal connection between said pair 65 of toggle levers.

5. In combination with a wall having a door opening therein and a pivotally mounted door adapted to close said door opening, means for operating said door comprising a bracket secured to the door frame of said wall, the pivotal mounting of the door extending through said bracket, an arm on said mounting, a sliding bar on 70 said bracket, a link connection between said arm and said bar, a second arm pivoted on said bracket at substantially right angles to the arm on said mounting, a platform mounted for depression when a weight is placed thereon, and a link connection 75 between said platform and said second arm.

6. A device of the class described comprising a wall, a door opening therein, a pair of platforms hinged at points spaced from said door opening and having their 80 free ends terminating adjacent each other, a shaft arranged in said door opening, a door secured thereto whereby rotation of said shaft will open said door, an actuating rod pivoted to the free ends of said platforms and connecting means between said rod and said shaft whereby depression of 85 said platforms will cause said doors to be opened.

7. In combination with a wall having a door opening therein and a pivotally mounted door adapted to close said door opening, means for operating said door comprising a bracket secured to the door frame of said wall, the pivotal mounting of the door extending through said bracket, an arm on said mounting, a sliding bar on 90 said bracket, a link connection between said arm and said bar and a platform connected to said bar for sliding it when said platform is depressed.

8. In combination with a wall having a door opening therein and a pivotally mounted door adapted to close said door opening, means for operating said door comprising a bracket secured to the door frame of said wall, the pivotal mounting of the door extending through said bracket, an arm on said mounting, a sliding bar on 100 said bracket, a link connection between said arm and said bar, a second arm pivoted on said bracket at substantially right angles to the arm on said mounting, and a platform connected to said second arm for sliding it 105 when said platform is depressed.

Des Moines, Iowa, March 22, 1927.
CLARENCE B. BATES.
